J. CHOMOS.
WINDOW LOCKING DEVICE.
APPLICATION FILED DEC. 19, 1919.
1,352,114.

Patented Sept. 7, 1920.

UNITED STATES PATENT OFFICE.

JOHN CHOMOS, OF TOLEDO, OHIO.

WINDOW-LOCKING DEVICE.

1,352,114.

Specification of Letters Patent.

Patented Sept. 7, 1920.

Application filed December 19, 1919. Serial No. 346,103.

To all whom it may concern:

Be it known that I, JOHN CHOMOS, citizen of Hungary, and resident of Toledo, in the county of Lucas and State of Ohio, have 5 invented certain new and useful Improvements in Window-Locking Devices, of which the following is a specification.

This invention relates to window locks and especially to that type which holds the 10 window sash in any position.

The object of this invention is the provision of simple and efficient means whereby the window sash can be quickly raised or lowered and locked in any desired position, 15 locking up.

A further object of this invention is the provision of window holding means which eliminates the necessity for using sash weights for holding the window in position.

20 For the accomplishment of the aforesaid objects I employ the devices shown in their preferred form in the accompanying drawings, in which:

Figure 1 is a front elevation of a window 25 to which my improved device has been attached.

Fig. 2 is a vertical section on line 2—2 of Fig. 1.

Fig. 3 is a horizontal section on line 3—3 30 of Fig. 1.

Fig. 4 is a vertical section on line 4—4 of Fig. 2, some of the parts being exaggerated for clearness.

In the practical embodiment of my invention, the vertical racks 1 and 2 are inserted 35 in the simple window frame 3 adjacent to sashes 5 and 20 respectively so that the teeth 4 of said racks face toward the center line of the window. The lower sash 5 has 40 pinions 6 at the corners thereof adapted to engage racks 1 on either side, said pinions being mounted on studs 7. Members 8 having slots 9 therein are shaped at the ends 10 so as to fit between the teeth 11 of said 45 pinions.

Guide rods 12 in said slots 9 act to force members 8 to move horizontally. The pin 50 13 in the end of member 8 is arranged for engagement with cam slot 14 of disk plate 15 which is mounted on stud 16 and which can be rocked by means of handle 17. The lower rail 18 of sash 5 has groove 19 cut therein for allowing pinions 11, members 8 and disk 15 to be set in said rail.

The means shown for holding sash 20 in 55 the desired position consist of thumb lever 21, having the bend 22 thereon which passes through opening 23 in the upright parts of said sash, said lever 21 being pivotally mounted on bracket 24 at joint 25. The end 60 of bend 22 is shaped to fit between the teeth of rack 2, said end being normally forced into contact with said rack by means of spring 26.

To raise sash 5, handle 17 is turned toward the right from the position shown in 65 Fig. 4, whereby pins 13 move in cam slots 14 nearer the center of stud 16, causing members 8 to move toward each other out of engagement with teeth 11 of pinions 6. The sash 5 is now free to be raised. The raising 70 of said sash causes pinion 6 to rotate because of its engagement with rack 1, and, there being two pinions 6 on each side, there is no lost motion laterally. When the desired position of said sash is reached, handle 75 17 is turned back to the left forcing members 8 into reengagement with pinions 6 whereby said pinions are prevented from rotating and the sash 5 is held firmly in place.

To move sash 20, the lower parts of levers 25 are pressed in toward the sash from releasing the engagement of bends 22 with racks 2 and allowing said sash 20 to be dropped into any desired position at which 85 point levers 21 are released allowing bends 22 to again engage racks 2 whereby sash 20 is locked in position.

It is obvious that the device shown for locking sash 20 may be replaced by a device 90 similar to that shown for holding sash 5 in position. It will also be seen that a lock connecting sash 20 to sash 5 for preventing the opening of the window from the outside is unnecessary because each sash is locked 95 in place separately. No sash weights being required to hold the window in position, a simple form of window frame 3 may be used, and weights, pulleys and cords eliminated.

100 What I claim is:

In combination with a window sash having an upwardly extending groove cut in the lower rail thereof, a stationary rack, a revoluble pinion in said groove revolvably 105 mounted in the corner of said lower rail for engaging said rack, a slidble member having a longitudinal slot therein positioned in

2
said rail groove, stationary pins in said rail passing through the slot in said member for allowing only longitudinal movement of said member, a tooth on the end of said member 5 for engaging one of the spaces between the teeth of said pinion, a pin on the other end of said member, a slotted cam disk, said last mentioned pin being arranged to engage one of the cam slots in said disk, a stud mounted 10 in said rail on which said disk is mounted,

and a handle on said disk projecting upwardly through said rail for rotating said disk to cause said member to engage and to be disengaged from said pinion whereby rotation of said pinion is prevented.

Signed at Toledo in the county of Lucas and State of Ohio this 15th day of December A. D. 1919.

JOHN CHOMOS.
